United States Patent Office

Des. 215,246
Patented Sept. 16, 1969

215,246

STENOTYPE MACHINE

Marcel Leroy, Paris, France, assignor to Stenotype
Grandjean, Société Anonyme, Paris, Seine, France

Filed May 10, 1968, Ser. No. 11,884

Term of patent 14 years

Int. Cl. D18—01

U.S. Cl. D64—11

Fig. 1

Fig. 2

Fig.3

Fig. 4

FIG. 1 is a front elevational view of a stenotype machine, showing my new design;

FIG. 2 is a left side elevational view thereof, the undisclosed right side being substantially similar in appearance;

FIG. 3 is a plan view thereof; and
FIG. 4 is the rear view thereof.

I claim:

The ornamental design for a stenotype machine, as shown and described.
